UNITED STATES PATENT OFFICE

111,109

DESIGN FOR A CASING FOR COMBINED WASHING MACHINE AND DRIER

John R. Morgan, Oak Park, Ill., assignor to Sears, Roebuck and Co., Chicago, Ill., a corporation of
New York

Application April 29, 1937, Serial No. 69,066

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Casing for Combined Washing Machine and Drier, of which the following is a specification, reference being had to the accompanying drawing, forming a part thereof.

Figure 1 is a top plan view of a casing for combined washing machine and drier embodying my new design, and

Figure 2 is a front perspective view thereof.

I claim:

The ornamental design for a casing for combined washing machine and drier, as shown.

JOHN R. MORGAN.
